UNITED STATES PATENT OFFICE.

OTTO M. SUMMERS, OF DAYTON, OHIO, ASSIGNOR, BY MESNE ASSIGNMENTS, TO
FRIGIDAIRE CORPORATION, A CORPORATION OF DELAWARE.

REFRIGERATING APPARATUS.

Application filed July 21, 1926. Serial No. 123,922.

This invention relates to refrigerators comprising a cabinet containing a cooling unit, and mechanical refrigerating apparatus for circulating refrigerant through the cooling unit.

Hitherto, mechanical refrigerators in which the mechanical apparatus is contained within the refrigerating cabinet have been objectionable, in that the vibration produced 10 by the moving parts, such as, for example, the compressor and driving motor, is transmitted directly to the cabinet, thereby amplifying the noise produced by the moving parts and at the same time causing the cabinet to "creep" or move from its original place.

It is desirable to assemble the refrigerating apparatus within the cabinet at the factory, because the apparatus may be charged 20 with the refrigerant medium and tested at the factory and then shipped to the consumer in condition for immediate operation; whereas, if the cabinet and apparatus are shipped separately, it would be necessary to 25 have them re-assembled and the apparatus re-charged and tested at their destination.

It is an object of this invention to provide a refrigerating cabinet in which the refrigerating machine may be assembled at the 30 factory and shipped with the cabinet as a unitary structure; and which can be adjusted when installed so that the vibration of the machine will not be transmitted directly to the cabinet. This object is accomplished by 35 providing for the support of the refrigerating machine by the cabinet during shipment and by providing for the release of the machine from the cabinet when installed while maintaining the connection between the machine and the cooling unit within the cooling chamber of the cabinet.

Another object of this invention is to provide means for absorbing the vibration incident to the operation of a refrigerating 45 compressor and motor.

Further objects and advantages of the present invention will be apparent from the following description, reference being had to the accompanying drawings, wherein a preferred form of the present invention is clearly shown.

In the drawings:

Fig. 1 is a front elevational view, partly

broken away, of a refrigerator embodying this invention; and

55

Fig. 2 is a fragmentary view on an enlarged scale, showing one of the supports for the base of the refrigerator.

The refrigerator cabinet 10 includes an upper cooling compartment 11 and a lower compartment 12. Compartment 11 is cooled by a suitable unit 13. A base 14 is provided in the machine compartment on which is mounted a refrigerant circulating unit which is herein shown for illustration as a compressor 15 driven by a motor 16. The compressed refrigerant gas is forced into the condenser 17 which may be mounted on the base, if desired. The condensed refrigerant is forced into the evaporator 18 through a conduit 18, and the expanded gaseous refrigerant is withdrawn therefrom through a conduit 19.

A bolt 20 passes upwardly through an aperture 21 in the base 14 and through an aperture 22 provided in a horizontal supporting member 23. The member 23 is rigidly attached to a wall of the machine compartment. The bolt 20 is provided with a nut 24, and a cotter pin 25 is placed at the extremity of the bolt, to prevent the nut from being accidentally removed. A yieldable washer 26, of rubber or similar material, is interposed on the bolt between the base 14 and supporting member 23. Likewise, a washer 27, preferably of felt, is interposed between the supporting member 23 and the nut 24.

Base 14 is provided with legs 28, each of which carries at its lower end a yieldable bumper or button 29, which may be of rubber. Similar bumpers or buttons 30 are also provided on the corner posts 31 of the cabinet.

Base 14 is supported as shown in Fig. 2 at 95 a plurality of places, preferably three. The bolt 20 is of such a length that, when its nut is drawn up tightly, the base will be free from the floor 32 on which the refrigerator is placed, whereby the weight of the compressor and motor will be carried by the cabinet through the supporting members 23. In this position, the cabinet and the assembled refrigerating apparatus are in condition for shipment as a unit; and, when the cabinet is 100 installed, it is necessary only to loosen the 105

nuts until the base 14 rests on the floor. Therefore, when the machine is operating, vibrations produced thereby will not be transmitted directly to the cabinet. The buttons 29 which support the base 14 tend to absorb the vibrations of the machine and to prevent vibration of the floor.

The conduits 18 and 19 are provided with suitable bends or turns 33 and 34, respectively, which permit the raising and lowering of the compressor without disturbing the operating connections between the compressor, condenser, and the evaporator.

It will thus be seen that it is possible to install the refrigerating apparatus, including the compressor, condenser, evaporator and their operating connections within the cabinet, at the factory, and to charge, test, and adjust the same. Then, by drawing up the nuts 24 and making the connections between the base and supporting members 23 rigid, the cabinet and assembled apparatus may be shipped as a unit. When the cabinet is then installed, it is but necessary to loosen the nuts, permitting the base to rest on the floor, whereupon the refrigerator will be in condition for operation with the cabinet free from machine vibrations.

While the form of embodiment of the present invention as herein disclosed, constitutes a preferred form, it is to be understood that other forms might be adopted, all coming within the scope of the claims which follow.

35 What is claimed is as follows:

1. A mechanical refrigerator comprising a cabinet having a cooling compartment and a machine compartment; a cooling unit in the cooling compartment; a refrigerant circulating unit in the machine compartment; operative connections between said units; and means for supporting the circulating unit from the cabinet and for permitting the release of such unit from the support at 40 will without disturbing the operative connections between said units and without disturbing the position of the cooling unit in the cooling compartment.

2. A mechanical refrigerator comprising a cabinet adapted to rest on a floor and having an upper cooling compartment and a lower machine compartment; a cooling unit in the cooling compartment; a compressor-condenser unit in the machine compartment; operative connections between the aforesaid units; and means permitting the compressor-condenser unit to be carried by the cabinet or supported by the floor at will while the operative connections between the aforesaid units remain intact and while the cooling unit remains in the cooling compartment.

3. A mechanical refrigerator comprising a cabinet adapted to rest on a floor and having an upper cooling compartment and a lower machine compartment; a cooling unit

in the cooling compartment; a base in the machine compartment, said base carrying a compressor, a condenser and a motor for driving the compressor; operative connections between said compressor, condenser and cooling unit; and means permitting the base to be carried by the cabinet or supported by the floor at will while the aforesaid operative connections remain intact and while the cooling unit remains in the cooling compartment.

4. A mechanical refrigerator comprising a cabinet adapted to rest on a floor and having a cooling compartment and a machine compartment; a cooling unit in the cooling compartment; a base in the machine compartment, said base carrying a compressor, a condenser and a motor for driving the compressor; operative connections between said compressor, condenser and cooling unit; means permitting the base to be carried by the cabinet or supported by the floor at will while the aforesaid operative connections remain intact and while the cooling unit remains in the cooling compartment; and means carried by the base for absorbing vibrations caused by the motor and compressor while the base is resting on the floor.

5. A mechanical refrigerator comprising a cabinet adapted to rest on a floor and having a cooling compartment and a machine compartment; a cooling unit in the cooling compartment; a base in the machine compartment, said base carrying a compressor, a condenser and a motor for driving the compressor; operative connections between said compressor, condenser and cooling unit; means permitting the base to be carried by the cabinet or supported by the floor at will while the aforesaid operative connections remain intact and while the cooling unit remains in the cooling compartment; and resilient bumpers carried by the base for absorbing vibrations caused by the motor and compressor while the base is resting on the floor.

6. A mechanical refrigerator comprising a cabinet adapted to rest on a floor and having a cooling compartment and a machine compartment; a cooling unit in the cooling compartment; a base in the machine compartment, said base carrying a compressor, a condenser and a motor for driving the compressor; operative connections between said compressor, condenser and cooling unit; supports carried by said machine compartment; bolts passing through apertures in said base and apertures in said supports; and means carried by said bolts whereby said base may be carried by said cabinet or supported by the floor at will while the operative connections between the aforesaid units remain intact and while the cooling unit remains in the cooling compartment.

7. A mechanical refrigerator comprising a

- cabinet adapted to rest on a floor and having an upper cooling compartment and a lower machine compartment; a cooling unit in the cooling compartment; a base in the 5 machine compartment, said base carrying a compressor and a motor for driving same; a condenser; operative connections between said compressor, condenser and cooling unit; and means permitting the base to be carried by the cabinet or supported by the floor at will while the aforesaid operative connections remain intact and while the cooling unit remains in the cooling compartment.
- 10 8. A mechanical refrigerator comprising a cabinet having a cooling compartment and a machine compartment; a cooling unit in the cooling compartment; a refrigerant circulating unit in the machine compartment; operative connections between the aforesaid units; means for supporting said units rigidly in said cabinet with said units opera-
- tively connected, said connections being adapted to permit relative detachment of one of said units from said supporting means without disturbing said operative connections and without disturbing the position of the other unit in its compartment.
- 15 9. A mechanical refrigerator comprising a cabinet adapted to rest on a floor and having a cooling compartment and a machine compartment; a cooling unit in the cooling compartment; a refrigerant circulating unit in the machine compartment; operative connections between the aforesaid units; and means permitting the circulating unit to be carried by the cabinet or supported by the floor at will while the operative connections between the aforesaid units remain intact and while the cooling unit remains in refrigerating position in the cooling compartment.
- 20 In testimony whereof I hereto affix my signature.

OTTO M. SUMMERS.
